LANCELOT MARTIN SIMPSON, OF THORNER, NEAR LEEDS, ENGLAND, ASSIGNOR TO
ASSOCIATED TELEPHONE AND TELEGRAPH COMPANY, OF KANSAS CITY, MISSOURI,
A CORPORATION OF DELAWARE

TELEPHONE SYSTEM

Application filed November 30, 1927, Serial No. 236,715, and in Great Britain April 28, 1927.

The present invention relates to telephone systems; more particularly to systems employing automatic numerical switches in serial relationship and is especially applicable to the routine testing of repeaters, relay groups, and so-called first code selectors, though certain of its features are capable of wider application. In many cases the numbering scheme will not permit the allocation of a selector level for routine testing purposes and the object of the present invention is to enable the testing to be carried out over a selector level without a corresponding sacrifice of numbers, a particular subscriber's number being used as the test number.

With final selectors arranged for battery feeding, the normal negative and positive line conductors cannot be used for testing purposes owing to the condensers and battery feed relays associated therewith in the final selector. In order to ascertain whether repeaters, relay groups and first code selectors of the type considered are functioning correctly, it is necessary to operate them through various resistances and for this purpose a clear metallic circuit for the operating impulses is necessary. The routiner circuit is arranged to supply ringing current and the impulses necessary to operate switches of the type considered, but it should be understood that the present invention is not limited to the use of any particular routiner circuits although in order that the invention may be more clearly understood reference may be made to application of John Ellis Ostline, Serial No. 222,456, filed September 28, 1927, in which a detailed description of the operation of an appropriate routiner is given.

According to one feature of the present invention the required objects are attained by the use of an automatic switch adapted to hunt to find a marked contact in which the special marking consists in the application of alternating current to the required contact.

In order that the invention may be more fully understood and readily carried into effect, a system making use of the principles of the invention will now be described with

reference to the accompanying single sheet of drawings. It will be understood, however, that this arrangement is given by way of example only and that various alterations may be made in the circuit details without exceeding the scope of the invention. 55

Figure 1 shows the trunking arrangement for routine testing first code selectors in a full automatic exchange, and Figure 2 shows the circuit arrangement of the auxiliary 60 equipment located between the routine testing equipment and the connector.

Referring to Figure 1, an ordinary local call from the substation SA to substation SB is set up over the rotary line switch RLS, trunk relay group TRG, first code selector FCS, first numerical selector S, and connector FS to the subscriber SB. 65

An exchange attendant wishing to routine 70 test a group of first code selectors will operate a start key associated with the routine testing equipment RTE, whereupon the distributor switch DS will advance into engagement with the first switch in the group. If this trunk is free the routine testing equipment automatically sends out the test number. Should the first trunk be busy, the impulse sending apparatus in the routine testing equipment delays sending for a predetermined interval and then steps on to the 75 next trunk. Assuming that the trunk relay group shown in the drawing is idle, the routine equipment RTE will send out the necessary impulses to extend the connection to the number allocated for testing purposes 80 in the bank of the connector. 85

The extension of the connection to this number causes the trunk finder TF to find the trunk incoming to the connector and to switch the connection from the selector S into 90 the routiner and disconnect the trunk to the connector.

Referring now to Figure 2, the equipment illustrated comprises a trunk finder TF, switching relay SR and auxiliary relays AR¹, AR², AR³, AR⁴. The switching relay SR is individual to each connector of the group in which its test number appears. The auxiliary relays AR¹, AR², AR³, AR⁴ and the trunk finder TF are common to the 95 100

group of connectors. When the connector FS is set on the test number, ground is extended over the private wiper P^2 to relay AR³ which takes the place of the regular subscriber's cut off relay. Relay AR³ upon operating, connects the number unobtainable tone conductor NUT to the negative bank contact B² and speaking conductor at armature 12 and at armature 10 connects the ground time pulses conductor PC to the two step pulse absorbing relay AR⁴. Pulses at the rate of 10 pulses per second are connected to the conductor PC.

The first pulse on conductor PC will cause two-step relay AR⁴ to close its X contacts and when this pulse is removed relay AR⁴ will energize over both its windings in series in the following circuit: battery, lower and upper windings in series, X contacts, armature 25 of relay AR² and its back contact to the grounded holding conductor HC. Relay AR⁴ now operates and at armature 13 extends the pulse conductor PC to the driving magnet DM of the trunk finder TF.

During this period the routiner RTE is arranged to connect ringing current to the positive line conductor A. The trunk finder is operated by pulses from conductor PC and advances its wipers 14, 15, and 16 until wiper 14 finds the contact to which ringing current is connected. When wiper 14 engages a contact to which ringing current has been applied a circuit is completed for the alternating current relay AR¹ which energizes in the following circuit: ground, relay AR¹, condenser C, wiper 14, armature 17 of relay SR and its back contact, conductor A, to ringing current connected up in the routiner. Relay AR¹ upon operating, connects at armature 22, the holding conductor HC, which is grounded in the routiner, to the switching relay SR over wiper 15. Relay SR upon operating, completes a locking circuit for itself to the holding conductor HC at armature 20, and at armatures 17 and 18 disconnects the positive and negative speaking conductors A¹, B¹ from the positive and negative speaking conductors A, B leading to the connector FS and extends them to the impulse accepting relay in the routiner over the common conductors A², B² and at armature 19 disconnects the private conductor P¹ of the incoming selector trunk from the private conductor of the connector trunk and grounds the former, thereby rendering it busy to other switches and to hold up the preceding switches. The connector now releases and removes ground from private wiper P^2 , this however, is without effect as the trunk finder TF has ceased hunting. Relay SR, at armature 21, also completes a circuit for relay AR². Relay AR² upon operating, opens the locking circuit for two step pulse absorbing relay AR⁴ at armature 25 and at armature 26

completes a homing circuit for the driving magnet DM. The number unobtainable tone is connected to the negative line of the test number in case a subscriber should dial the test number by mistake, when he will receive the usual dead number tone signal. 70

At the end of routine testing operation ground potential is removed from the holding conductor HC whereupon switching relay SR releases and opens its own locking circuit at armature 20 and connects the incoming trunk to the connector FS again at armatures 17, 18 and 19. It sometimes happens that an exchange attendant will advance the wipers of the trunk finder TF by hand and in order to ensure that this switch will be returned to its normal position the following circuit is arranged over its wiper 16 and interrupter contacts 27; ground resting contact and armature 11, resting contact and armature 26, wiper 16 and its associated common bank contacts, interrupter contacts 27, winding of magnet DM to battery. 75 80 85

What is claimed is:

1. In a telephone system, a switch having a contact bank, means for marking any contact in that bank with alternating current, and means for operating said switch to hunt for said marked contact. 90
2. In a telephone system, selector switches, connector switches, means for establishing a connection over a path including one of each of said switches, and means responsive to the establishment of a connection for releasing the connector switch and connecting the selector switch to the first mentioned means. 95
3. In a telephone system, a group of primary switches, a group of secondary switches, means for establishing a connection over one of each of said switches, and an auxiliary switch responsive to the establishing of a connection for hunting for the secondary switch in the connection and for thereafter releasing the secondary switch and connecting the primary switch to said means. 100 105 110
4. In a telephone system, selector switches, connector switches, a plurality of means for establishing connections over paths including one of each of said switches, and means responsive to the establishment of connections by certain of said first means for releasing connectors in said connections and connecting the selectors to said certain means. 115
5. In a telephone system, selector switches, connector switches, means for establishing a connection over one of each of said switches, testing equipment having means for establishing a connection over one of each of said switches, and means responsive to the establishment of a connection by said equipment for releasing the connector and connecting the selector to said equipment. 120 125
6. In a telephone system, selector switches, connector switches, means for establishing a connection over one of each of said switches, 130

5 testing equipment having means for establishing a connection over one of each of said switches, also, and an auxiliary switch operated responsive to the establishment of a connection by said equipment for disconnecting the selector switch from the connector switch and connecting the selector switch to said equipment.

10 7. In a telephone system, selectors, connectors, trunks, means for establishing a connection over a path including one of said selectors, one of said trunks and one of said connectors, and an auxiliary switch operated responsive to the establishment of a connection 15 for hunting for the connecting trunk and for thereafter switching said trunk from said connector to said means.

20 8. In a telephone system, selector switches, trunks, connector switches accessible to said selectors over said trunks, means for establishing a connection over a path including one of said selectors, one of said trunks and one of said connectors, testing equipment having means for establishing a connection over a 25 similar path, and an auxiliary switch operated responsive to the establishment of a connection by said equipment for hunting for the trunk in that connection and for thereafter disconnecting said trunk from the connector 30 switch and connecting it to said equipment.

25 9. In a telephone system, selector switches, trunks, connector switches accessible to said selectors over said trunks, means for establishing a connection over a path including one of 35 said selectors, one of said trunks and one of said connectors, testing equipment having means for establishing a connection over a similar path, means in said equipment for projecting alternating current over the trunk 40 in the connection established thereby, and an auxiliary switch operated responsive to the establishment of a connection by said equipment for hunting for the trunk marked by alternating current and for thereafter causing 45 said trunk to be disconnected from the connector and connected to said equipment.

10. In a telephone system, selector switches, trunks, connector switches accessible to said selector switches over said trunks, testing 50 equipment having means for establishing a connection over a path including one of said selectors, one of said trunks and one of said connectors, means in said equipment for projecting alternating current over said trunk, 55 and an auxiliary switch operated responsive to the establishment of said connection for hunting for said trunk, an alternating current relay in said auxiliary switch operated responsive to the finding of said trunk, and 60 means associated with said trunk and operated responsive to the operation of said relay for disconnecting said trunk from the connector switch and connecting the trunk to said equipment.

65 11. In a telephone system, a switch having

a contact bank and having a normal position, means for marking any contact in that bank with alternating current, means for operating said switch from its normal position to hunt for said marked contact, and means automatically operated when said marked contact is 70 found for operating said switch to return it to its normal position.

In witness whereof, I hereunto subscribe my name this 7th day of November, A. D. 75 1927.

LANCELOT MARTIN SIMPSON.
